UNITED STATES PATENT OFFICE

149,007

DESIGN FOR A SPECTACLE FRAME

Golda Lewis, New York, N. Y.

Application April 24, 1947, Serial No. 138,593

Term of patent 7 years

(CL. D57—1)

To all whom it may concern:

Be it known that I, Golda Lewis, a citizen of the United States, residing at New York, in the county of New York and State of New York, have invented a new, original, and ornamental Design for a Spectacle Frame, of which the following is a specification, reference being had to the accompanying drawing, forming part thereof.

Figure 1 is a top plan view of a spectacle frame, showing my new design, the essential features of which are disclosed by means of full lines.

Figure 2 is a front elevational view thereof, and

Figure 3 is a cross-sectional view, taken substantially in the plane of the line 3—3 in Figure 2.

My design for a spectacle frame is character-

ized by the specific type and configuration of the projecting extensions above the lenses, as seen most clearly in Figures 1 and 3 and suggesting eye lashes of a human being.

I claim:

The ornamental design for a spectacle frame, as shown and described.

GOLDA LEWIS.
